UNITED STATES PATENT OFFICE.

ELMER HARRISON, OF DETROIT, MICHIGAN.

STEAM-GENERATOR.

1,142,420.

Specification of Letters Patent. Patented June 8, 1915.

Application filed May 1, 1913. Serial No. 764,740.

To all whom it may concern:

Be it known that I, ELMER HARRISON, a citizen of the United States of America, residing at Detroit, in the county of Wayne 5 and State of Michigan, have invented certain new and useful Improvements in Steam-Generators, of which the following is a specification, reference being had thereto in the accompanying drawings.

10 This invention relates to an improved generator especially adapted for house heating and similar purposes where a low pressure of steam is required and where it is desirable to have an automatic regulation 15 thereof.

15 The object of the invention is to provide a simple and inexpensive construction especially adapted for the purpose and for use in conjunction with a gas burner as the 20 source of heat.

20 A further object is to provide a simple and efficient regulation for automatically regulating the supply of fuel in proportion to the steam pressure and to provide certain 25 other new and useful features in the construction and arrangement of parts.

25 To these ends the invention consists in the matters hereinafter set forth and more particularly pointed out in the appended 30 claims, reference being had to the accompanying drawing in which the figure represents a central vertical section through a device embodying the invention.

35 A tank or boiler 1 of vertical tubular form is provided to contain a quantity of water in its lower end, the height of the water being regulated by an inlet valve 2 at the end of a feed pipe 3, said valve having a stem 4 extending into the tank and engaged at its inner end by the short arm 5 of a bell crank lever to the long arm 6 of which is attached a float 7 so that as the water level rises or falls in the tank the valve will be operated by the float and opened or 45 closed.

45 Any suitable stand 8 is provided to support the tank 1 in a vertical position and this tank has a conical bottom 9 provided with an axial discharge pipe controlled by 50 a valve 10 so that the contents of the tank may be drawn off if desired. The upper end 11 on the tank is preferably dome shaped and leading from it is a steam pipe 12 for conducting the steam to the place 55 where it is to be used, as in heating coils, etc. In the axis of the dome 11 is an open-

ing within which is secured a tubular stem 13 on the head of the bellows 14. The opposite or inner head 15 of the bellows is provided with a rod 16 extending upward 60 through the bellows and through the tubular stem 13, the bellows being steam tight and adapted to be compressed by internal steam pressure within the tank, the leaves or folds 17 of the bellows being formed of 65 spring metal in the usual manner so that when the steam pressure falls the bellows will automatically expand. Upon the outer end of the rod 16 is a rack 18 which is engaged by a sector 19 having an arm 20 to 70 the opposite end of which a link 21 is pivotally attached to connect it to a bell crank lever 22 pivotally supported upon the upper end of the tank. A connecting rod 23 is pivotally attached at the end to a bell crank 75 22 and extends downward and has suitable connection at its lower end with the arm 24 of a valve 25 located within a gas supply pipe 26. The rod 23 is provided with a turn buckle 27 so that it may be adjusted 80 as to length and vary the position of the arm 24 to control the opening and closing of the valve 25 by the operation of the bellows and consequent movement of the rod 23.

85 A heater 28 comprises a suitable tubular body having headers 29 and 30 for the fire tubes 31 which are secured within the headers and open therethrough. The upper end of the heater body is closed by a breeching 32 from which leads a smoke pipe 33. The 90 lower end of the body of the heater is secured to a suitable base 34 which is supported upon a bracket 35 attached to the side of the stand 8 and within the base 34 is supported a suitable burner 36 of any 95 desired construction having a mixing tube 37 extending outward through the side of the base and provided with a mixing valve 38 at its outer end into which the end of the gas supply pipe 26 discharges. The supply 100 pipe is provided with a shut-off valve 39 and a drain cock 40 is provided in the heater body adjacent to the head 29. The connection 41 between the lower end of the tank 1 and the lower end of the heater body 105 prevents communication between the two and allows the water from the tank to flow into the heater around the fire tubes 31 and rise therein to the level which is maintained by the float 7 within the tank. A steam 110 discharge pipe 42 is connected to the heater body above the level of the water therein

and at its opposite end opens into the upper end of the tank 1 to conduct the steam generated in the heater into the upper end of the tank from which it will flow through the pipe 12 to the place of use. A water gage 43 may be provided on the side of the heater body if so desired, and a suitable connection 44 is provided on the dome 11 of the tank for a steam gage, not shown.

10. In the operation of the device, water is maintained at the desired level within the tank and heater by means of the float 7. Gas is turned on by means of the shut-off 39 and the burner 36 is lighted. The flames and products of combustion from the burner pass directly up the fire tubes 31 and quickly heat the water in the heater around the tubes transforming it into steam which passes off through the pipe 42 into the steam space in the tank 1 above the water therein. As the steam pressure in the tank rises, the bellows 14 is compressed thereby thus causing the rod 36 to be moved outwardly through the stem 13 and the rack 18 to be actuated. The movement of the rack causes a corresponding movement in the sector and arm 20, and motion is transmitted therefrom by the suitable connections to the arm 24 of the controlling valve 25 of the gas supply pipe. The supply of gas to the burner is therefore automatically regulated by the pressure of steam within the tank and will be turned off or on to a greater or less degree as the steam pressure rises or falls.

15. A very simple and cheap steam generator having an automatic regulation is thus provided and it is especially adapted for use as a house heating plant and for similar purposes.

20. Having thus fully described my invention what I claim is:—

1. The combination of a tank, a heater in communication with said tank and adapted to supply steam thereto generated from water supplied to said heater from said tank, a burner in said heater, a gas supply pipe connected to said burner, and pressure actuated means within said tank for controlling the supply of gas to said burner, said means including a rod extending out of said tank, a rack on said rod, a sector engaging said rack, and a valve indirectly operated by a movement of said sector.

2. The combination of a tank having a water connection, a heater in communication with said tank and adapted to supply steam thereto generated from water received from said tank, means within said tank for maintaining a constant level of water within said tank and said heater, a burner below said heater, a bellows located in the upper part

of said tank and adapted to be actuated by internal steam pressure within the tank, and a rack actuated by said bellows for controlling the operation of said burner.

3. The combination of a tank, a heater, a water connection between the lower end of the tank and the lower end of the heater, a steam connection between the upper end of the heater and the upper end of the tank, means for maintaining a water level in the tank and heater, a gas burner for the heater, a gas supply pipe for the burner, a regulating valve in the gas supply pipe, a bellows in the upper end of the tank, a tubular nipple on the bellows extending upward through the end of the tank, a rod secured to the inner end of the bellows and extending outward through the nipple, a rack on the rod, a sector engaging the rack, and means for transmitting motion from the sector to the controlling valve in the gas supply pipe for actuating said valve.

4. The combination of a tank, a heater outside the tank and adjacent thereto adapted to contain water, means for maintaining a common water level in the tank and heater with a steam space in the upper end of said tank and heater above the water level, a water connection between the tank and heater below the water level, a steam connection between the tank and heater above the water level to conduct steam generated in the heater into the steam space above the water in the tank to pre-heat the water therein, means for heating the heater, and means within the steam space in the tank for controlling the heating means.

5. The combination of a tank, a heater arranged in a vertical position at one side of and adjacent to the tank, said heater being adapted to contain water, means for maintaining a common water level in the tank and heater below the upper end of the heater to provide a steam space above the water in said tank and heater, a water connection between the tank and heater near the lower end of the heater, a sleeve connection between the tank and heater near the upper end of the heater above the water level, a burner for the heater, a fuel supply for the burner, and means within the steam space of the tank operated by steam pressure therein for regulating the supply of fuel to the burner.
